BUCKLE

Clarence E. Beatty, Colorado Springs, Colo.

Application September 9, 1940, Serial No. 355,910

3 Claims.

(Cl. 24—74)

This invention relates to improvements in buckles.

It is the object of this invention to produce a buckle of simple and substantial design that can be manufactured at a low cost and which shall be effective and ornamental in appearance.

Another object is to produce a buckle that does not require the belt or strap with which it is used to be provided with holes, but which employs a clamping action.

A further object is to produce a buckle that can be constructed entirely from wire or which can be made from a combination of wire and sheet metal and a still further object is to produce a double acting buckle that can be employed to connect two ends of a belt, band, or strap.

The above and any other objects that may become apparent as this description proceeds are obtained by means of a construction and an arrangement of parts that will now be described in detail and for this purpose reference will be had to the accompanying drawing in which the invention has been illustrated, and in which

Figure 1 is a top plan view of the improved buckle;

Figure 2 is a side elevation thereof;

Figure 3 is a bottom plan view;

Figure 4 is a section taken on line 4—4, Figure 1;

Figure 5 is a top plan view of another embodiment of the invention;

Figure 6 is a side elevation of the buckle shown in Figure 5;

Figure 7 is a side elevation showing the buckle illustrated in Figures 5 and 6 attached to a wrist band in such way that the band protects the skin from contact with metal parts, and

Figure 8 is a plan view showing a double ended buckle of the type shown in Figure 5.

Referring now to the drawing, reference numeral 10 designates a clamping member of resilient sheet metal of substantially the shape shown in Figure 1, in which two pairs of tongues 11 and 12 have been cut from the metal leaving openings 13 as shown in Figure 1. These tongues are bent into overlapping position as shown in Figure 2 so as to form bearings for the sides of rectangular frames which have been designated by reference numeral 14. The metal clamping member 10 is reversely bent at points 15, and the ends, which are turned back and which have been designated by reference numeral 16, are downwardly curved and outwardly concave and terminate at points 17. The frames

14 are preferably rectangular with either sharp corners or rounded corners as may be found most desirable. One of the parallel sides of each frame is fulcrumed in the bearings formed by tongues 11 and 12, and the other side is free to move about the pivot point. The parts are so proportioned that the distance from the axis of the pivots to the ends of the reversely bent end members 17 is slightly greater than the corresponding distance from the axis to the inner surface of the movable side of the frame and therefore the clamping member must bend slightly as the frame is moved about its pivot into and away from the position shown in Figure 4. The position of the ends 17 relative to the frame can be varied to get the best results with the particular thickness of belt or strap used, but due to the resiliency of the clamping members a considerable variation is permissible. It will be observed that the bends 15 are so positioned that they project beyond the free ends of the frames and overlap the ends 18 of a belt or strap 19 to which the buckle is secured in the manner shown in Figure 4. The ends 17 engage the bight of the belt and force the same against the frame while the overlapping ends of the plate 10 keep the ends of the belt pressed downwardly, whereupon a clamping action is obtained that holds the belt or strap quite firmly in position. When the buckle is to be applied to the ends of a strap or belt the frames are bent downwardly into the dotted line position shown in Figure 2, whereupon the belt can be readily threaded through the frame. The frame is now pressed upwardly against the reversely bent portion 16 and tension is applied to the belt, whereupon the ends 17 are moved into clamping position as shown in Figure 4. When the belt is to be released from the buckle, tension is supplied to the end or ends 18, whereupon the clamping member and the frames are moved into inoperative position.

The buckle just described lends itself to the construction of a wire and sheet metal buckle having the general appearance shown in Figure 1, whose surface can be ornamented or provided with initials or monograms corresponding to the owner's name.

In Figures 5, 6, and 7 a slightly modified form of construction has been shown in which the frame as well as the clamping member is made from wire or similar material. The frame is substantially rectangular and the ends which have been designated by reference numerals 20 may be slightly spaced apart if desired. The clamp-

ing member, instead of being made from resilient sheet metal, is made from resilient wire in which arms 21 terminate in loops 22 that encircle the frame adjacent the ends thereof. The arms 21 extend outwardly beyond the opposite side of the frame where they are bent at right angles at points indicated by reference numerals 23. They extend transversely to points 24, where they are again bent at right angles and downwardly and forwardly curved so that the curved portion which has been designated by reference numeral 25, extends to a point below the frame corresponding to the points 17 in Figure 4. The parts designated by reference numerals 26 correspond to the reversely bent portions 16 in Figures 1 to 4.

Buckles constructed in the manner shown in Figures 5 and 6 can be made at small cost and are very effective for the purpose intended. Such buckles are intended primarily for Army belts, for book straps, and for other uses where a substantial and inexpensive buckle is desired.

In Figure 7 a buckle of the type shown in Figures 5 and 6 has been shown as connected with a wrist-band or a garter, and it will be seen from this figure that the band or garter protects the skin from contact with the metal parts and therefore prevents discoloration or chafing due to such metallic contact. The manner in which the buckle is attached to the wrist-band is so clearly apparent from Figure 7 that a detailed description is believed to be unnecessary.

In Figure 8 a modification of the buckle shown in Figures 5 and 6 has been illustrated. In this modified form two frames 14 are employed in a manner corresponding to that of Figures 1 to 4. The clamping member which comprises the arms 21, instead of terminating in loops 22, extends in the opposite direction and provides arms 23a which correspond to arms 21 in Figure 5, and these are bent laterally and reversely as indicated by reference numerals 27 and 28. Parts 28 are downwardly and forwardly curved and terminate in ends 25a. When constructed in the manner shown in Figure 8, the buckle corresponds in almost every particular with that shown in Figures 1 to 3 and can be employed in the same manner for attaching the two ends of a belt or strap without first sewing or otherwise securing one end to the buckle as must be done when a construction like that shown in Figures 5 and 6 is employed.

Attention is called to the fact that in the several embodiments illustrated the clamping member extends beyond the movable end of the frame and this overlapping part of the clamp holds the end 18 of the belt or strap in a position substantially parallel to the belt portion indicated by reference numeral 19. The clamping action is effected by the ends 17 of the reversely bent portions of the member 10 and by the corresponding ends 25 and 25a of the clamping member shown in Figures 5 and 6.

Referring again to Figure 8, attention is called to the fact that the two clamping members 21 and 23a may be made separate instead of integral in which case the frame encircling loops 22 of the two clamping members are not interconnected, but separate thereby producing a double ended buckle comprising two buckles like that shown in Figure 5. The hinged construction just described is more desirable for some purposes than a construction in which the two clamp members are integral. If desired the clamping members of the double hinged buckle may be made of sheet

metal instead of wire. When the hinged construction just described is used, the two parts of the clamping member 23a may be soldered or welded along the part where they are in contact or both clamping members may be constructed in the same manner as the one at the lefthand of Figure 8.

A buckle constructed in the manner illustrated and described does not require the belt or strap to be provided with holes for the reception of tongues as is usual with belt buckles, and the parts are so constructed and designed that the buckle can be released by a pull on ends 18 and moved into operative position by a pull on the strap or belt portions 19.

Attention is called in particular to the great simplicity of this buckle, as the clamping member shown in Figures 1 to 4 can be formed by automatic machinery, and the same is true of the wire clamping member shown in the other embodiments.

Although applicant has described in detail three specific embodiments of his invention, it is to be understood that they are merely illustrative, and that the invention may be embodied in other forms and applicant therefore does not want to be limited to any greater extent than required by the scope of the appended claims when construed in accordance with the doctrine of mechanical equivalents.

In the above description the frame has been defined as "rectangular" or substantially so. It is to be understood that the sides 14 do not have to be parallel or straight as they merely serve to connect the other two sides, one of which forms the pivot and the other of which cooperates with the clamping member.

Attention is directed to Figure 4 from which it will be seen that when tension is applied to belt 19 any movement of the belt relative to the frames 14 tends to move points 17 in the same direction and urges the reversely bent ends 15 towards the belt thereby increasing the clamping action.

Having described the invention what is claimed as new is:

1. In a buckle having a substantially four-sided frame, a clamping member of resilient material pivoted to one side of the frame, the clamping member projecting beyond the other side of the frame where it terminates in a reverse bend, the reversely bent portion terminating in a downwardly extending forwardly concave portion.

2. In a buckle having a substantially four-sided frame, a clamping member of resilient material pivoted to one side of the frame, the clamping member projecting beyond the other side of the frame where it terminates in a reverse bend, the reversely bent portion terminating in a laterally extending portion concave away from the pivot, the distance from the pivot to the concave portion being substantially the same as the distance from the pivot to the opposite side of the frame.

3. In a buckle having a four sided frame, a clamping member of resilient material pivoted to one side of the frame, the clamping member projecting beyond the other side of the frame, said clamping member having a laterally extending portion concave away from the pivot, the distance from the pivot to the concave portion being substantially the same as the distance from the pivot to the opposite side of the frame.
